US00D554998S

(12) **United States Design Patent** (10) **Patent No.:** **US D554,998 S**
(45) **Date of Patent:** **** Nov. 13, 2007**

(54) **BOTTLE**

(75) Inventors: **Timothy Frederik Thomas Perry**,
London (GB); **Edward Adamson**,
London (GB)

(73) Assignee: **The Procter & Gamble Company**,
Cincinnati, OH (US)

(**) Term: **14 Years**

(21) Appl. No.: **29/286,349**

(22) Filed: **May 2, 2007**

Related U.S. Application Data

(62) Division of application No. 29/217,697, filed on Nov.
19, 2004.

(30) **Foreign Application Priority Data**

May 24, 2004 (EM) 000181466

(51) **LOC (8) Cl.** **09-01**

(52) **U.S. Cl.** **D9/516; D9/552**
